UNITED STATES PATENT OFFICE.

HARVEY R. FULLER, OF KIRKSVILLE, MISSOURI.

RULING-PEN.

1,348,637.

Specification of Letters Patent. Patented Aug. 3, 1920.

Application filed June 5, 1919. Serial No. 302,035.

To all whom it may concern:

Be it known that I, HARVEY R. FULLER, a citizen of the United States, residing at Kirksville, in the county of Adair and 5 State of Missouri, have invented certain new and useful Improvements in Ruling-Pens, of which the following is a specification.

This invention relates to drafting instruments and more particularly to an improvement in ruling pens. The ordinary ruling pen is provided with imperforate blades and the pen is filled by introducing ink into the space between the blades, it being customary to wipe off with a cloth the surplus ink 10 which may adhere to the outer surfaces of the said blades. This not only occasions a considerable waste of ink but the operation of filling is annoying and uncleanly. Furthermore, the ordinary ruling pen, even in 15 the larger sizes, is adapted to contain in the space between its blades only a relatively small quantity of ink so that more or less frequent filling of the pen is required with a consequent loss of time. In consideration 20 of the foregoing it is the primary object of the present invention to provide a ruling pen so constructed that the same will be adapted to contain a maximum quantity of ink in proportion to the size of the pen, and 25 which pen may be more readily and conveniently filled with ink than the ordinary pen and without likelihood of smearing the ink upon the outer surfaces of the blades, thus obviating the practice of wiping the 30 blades after the filling operation has been performed.

Another object of the invention is to provide a pen possessing the features above mentioned and which pen may be manufactured at substantially the same cost as 40 the ordinary ruling pen.

Another disadvantage presented in the ordinary ruling pen is that, except by turning the pen upon its side, the quantity of ink 45 in the pen cannot be determined, and therefore another important object of the invention is to so construct a ruling pen that the quantity of ink contained therein may be readily ascertained at a glance at any time 50 while the pen is in use without lifting the pen from the paper or otherwise interrupting the work of drafting.

Ruling pens of the ordinary construction further present the disadvantage that if the 55 blades are opened to any considerable extent in order to draw a very heavy line or if a

line is drawn with the pen intersecting another line which has not thoroughly dried, the ink is liable to flow from the pen so freely as to cause blotting. It is therefore another object of the invention to provide a ruling pen so constructed that the flow of ink therefrom will be retarded to a desirable degree so that this last named disadvantage 60 will be overcome.

In the accompanying drawings,

Figure 1 is a plan view of a ruling pen constructed in accordance with the present invention;

Fig. 2 is a side elevation of the pen;

Fig. 3 is a vertical transverse sectional view taken substantially on the line 3-3 of Fig. 1.

In the drawings the numeral 1 indicates the handle of the ruling pen, 2 the fixed or 75 relatively rigid blade thereof which blade is the one ordinarily presented to the straight edge, and 3 the resilient or adjustable blade, the adjustment of which is effected through the medium of the adjusting 80 screw 4. As is usual in pens of this class, the blades 2 and 3 are gradually tapered and also gradually decreased in thickness in the direction of their working or sharpened ends 5, the blade 3 being relatively thick except 85 at and adjacent its said working end.

The present invention resides, briefly stated, in providing in the blade 3, an opening, channel, or recess which will constitute an ink reservoir and will serve other purposes to be presently pointed out. Thus in the illustrated embodiment of the invention, the blade 3 is formed between its working end and the adjusting screw 4, with a longitudinally extending slot or opening 6, this opening being preferably of the triangular or wedge shape shown clearly in Fig. 1 of the drawings or, in other words, being of maximum width at its end next adjacent the adjusting screw 4, as indicated by the numeral 7, and being gradually decreased in width to its end located next adjacent the working end of the said blade 3. The side walls of the opening 6 are indicated by the numeral 8 and due to the above described 100 shape of this opening, these walls occupy planes converging in the direction of the working end of the pen.

From the foregoing and from a comparison of Figs. 1 and 2 and by reference to 110 Fig. 3, the opening 6 has a maximum width greater than the usual height of the space

between the inner faces of the blades of the pen. Thus the pen embodying the present invention may be more readily and conveniently filled by supplying the ink to 5 this space through the wider end of the opening 6, the ink filling not only the space between the inner faces of the blades but also more or less completely filling the said opening 6. Thus the opening 6 constitutes 10 a reservoir located in one of the blades of the pen and greatly increases the ink holding capacity of the pen. It will also be understood that due to the fact that the walls of the opening 6 converge in the manner 15 above stated, the flow of ink from the pen will be somewhat retarded because of the capillary attraction of the ink tending to retain a certain volume of the ink within the opening 6.

20 In order that the capacity of the reservoir may be greatly increased without the necessity of forming the blade 3 of extraordinary thickness, I preferably form this blade with an outstanding flange 9 located at that 25 side of the opening 6 which is located at the left when the pen is viewed from the front, this flange extending the entire length of the said side of the opening and at its lower end being extended laterally partly about 30 the lower end of the opening as indicated by the numeral 10. The inner face of this flange or, in other words, that face which is presented toward the opening, is flush and occupies a common plane with the corresponding wall of the opening. Of course, 35 by capillary attraction, the ink within the reservoir thus provided will be drawn to

the said face of the flange and consequently the capacity of the reservoir will be greatly increased. At the same time, the flange 40 serves as a guard against which the fore-finger or middle finger may rest in the use of the pen and be protected from becoming soiled with ink from the reservoir.

Having thus described the invention, what 45 is claimed as new is:

1. A ruling pen comprising two blades, one of said blades having a longitudinal channel constituting a reservoir, and an outstanding flange extending along one side of 50 said channel.

2. A ruling pen comprising two blades, one of said blades having an opening extending through the face thereof and constituting an ink reservoir, said blade being provided with an outstanding flange extending at one side of said opening. 55

3. A ruling pen comprising two blades, one of said blades having a longitudinally extending opening terminating at one end 60 adjacent the working end of the blade and constituting a reservoir, the said blade being provided with an outstanding flange extending along one side of the opening and about the said end of the opening. 65

4. A ruling pen comprising two blades, one of said blades having a longitudinally extending opening the side walls of which converge in the direction of the working end of the blade, the said blade being provided with an outstanding flange extending along one of the side walls of said opening. 70

In testimony whereof I affix my signature.

H. R. FULLER. [L. S.]
